Fig. 5.

The dominant features of my design reside in those portions illustrated in full lines, while the characteristic features thereof reside in a merged unitary relationship between a generally cylindrical container side wall, an inwardly curved integral closed upper end portion, and fingers projecting inwardly and upwardly from the upper end portion of the container as unitary parts thereof for supporting laterally projecting trunnions of a swingable dispensing spout, all as shown.

I claim:

The ornamental design for a dispensing container for liquids or the like, substantially as shown and described.
